METHOD OF MAKING PERFORATED CONCRETE PIPES

John Arborio, Poughkeepsie, N. Y.

Application August 25, 1937, Serial No. 160,834

6 Claims. (Cl. 25—154)

This invention relates to concrete pipes and method of making the same, and more particularly to a concrete pipe provided with perforations over a part of the circumference thereof, so that drainage water may enter the pipe from the upper side when the latter is laid horizontally.

Recently the making of concrete pipe has become of considerable importance in that many sizes and varieties of pipe are made of this material which were formerly made of tile. If handled correctly and if the proper methods are employed, concrete lends itself quite admirably to the making of pipes, as it can be poured or packed into forms of the desired shape, so that a pipe of the desired size and wall thickness will be obtained.

In the method herein described, a form is used for the exterior surface of the pipe. None, however, is employed for the interior. Instead a plunger or ram, having on its end what may be termed a packer head, is rotated within the pipe as the concrete is being delivered therein, so that the latter will be packed tightly against the wall of the form, and thus provide the interior opening. Moreover, in order to make a pipe having perforations or openings in the wall thereof, it is necessary to provide for such openings when the concrete is being packed. In order to do this, I pack the concrete about pins which project into the form, the inner ends of the pins, however, being just short of the inner surface of the pipe wall, so that there will be no danger of these pins interfering with the packer head. The concrete is formed about the pins, so that when the pins are removed from the pipe, perforations exist from the outer wall to a point within a very short distance of the inner wall. This small thickness of concrete or plug at the bottom of the hole may be easily punched out before the concrete has become fully set, so that clean-cut perforations formed entirely through the wall will be provided.

One object of the invention is to provide a novel and improved method of making concrete pipe.

Another object of the invention is to provide an improved method of making a concrete pipe having perforations in a portion of the wall thereof, the perforations preferably extending substantially throughout the longitudinal dimension of the pipe, but being provided in only a portion of the pipe circumferentially.

A still further object of the invention is the provision of a concrete pipe having drainage per-

forations formed in a portion only of the wall thereof.

To these and other ends the invention consists in the novel features and combinations of parts to be hereinafter described and claimed. 5

In the drawing:

Fig. 1 is a longitudinal sectional view of apparatus used in connection with the practice of my improved process;

Fig. 2 is a sectional view of the form used for 10 the concrete pipe; and

Fig. 3 is a sectional view on line 3—3 of Fig. 1.

To illustrate a preferred form of my invention, I have shown in the drawing certain apparatus for carrying out the process of making the concrete pipe. It may be noted that a form is employed substantially of the outside dimensions of the pipe to be made. The concrete is mixed and packed into this form by a suitable machine devised for this purpose. The concrete is in a very dry state, the expression "very dry" being relative, of course; as it is sufficiently moist to cause it to set. It is hardly more than moist, however, and not sufficiently wet so that it is at all fluid.

In the making of the pipe I employ a form of 25 generally cylindrical shape, such as shown at 10 in Fig. 1. This form is placed over a support 11 provided on a plunger 12, which support is movable in an opening in the floor or base 13. The support also carries a form block 14 of cylindrical shape, which is of smaller diameter and rests 30 within the lower portion of the form 10.

The lower end of the form is flared, as shown at 15, so that an annular space 16 remains between the form and the block 14 to provide the 35 end flange on the finished pipe.

Secured to the upper and lower ends of the form are lugs 17 and 18 which are held in grooves 19 and 20, which grooves are provided in members 21 and 22, secured respectively to the upper and lower supports 13 and 23. This will prevent the form from turning during the rotation of the packer head, as will be described herein-after.

The upper supporting member 23 is provided 45 with an opening 24 through which extends a plunger 25 carrying at its lower end a packer head 26, on the upper surface of which are provided a pair of blades 27 shaped to throw outwardly against the wall of the form any material which may fall in the path of these blades. 50 The packer head 26 may be moved downwardly to rest upon the block 14, which will be its position at the beginning of the packing operation. It will be noted that the size of the packer head 55

26 is that of the opening desired in the finished pipe, this opening being indicated by the dotted lines 28 in Figs. 1 and 2. That is to say, the dotted line 28 indicates the inner surface of the 5 finished pipe, the wall of which, of course, lies between this line and the inner surface of the form 10.

As shown in Fig. 2, attached to frames 30, mounted upon the wall of the form, are pins 31 10 which are movably mounted in the frames 30 and adapted to project through openings 32 in the wall of the form. These pins are provided in longitudinal rows or gangs, six of such gangs being shown in connection with the form illustrat- 15 ed, as will be seen from inspection of Fig. 2 of the drawing. The pins of one row or gang are secured to a bar 33, so that, by moving the bar, all of the pins of one gang may be moved in and out simultaneously to withdraw them from a pro- 20 tracted position within the form, and so withdraw them from the pipe after it has been packed when it is desired to remove the form. A retaining member 34 is rotatably mounted on a pin or bolt 35 attached to the form between two ad- 25 jacent bars 33, the member 34 being rotatable into the position shown in Fig. 2 to engage the bars, and hold the pins in protracted position, as shown in Fig. 2, by reason of the action of the compression spring 36, which bears against the 30 nut 37 on the bolt 35 at one end, and at its other end upon the retaining member 34. The pins are thus resiliently held in protracted position, but may be retracted from the form when the retaining member is rotated through an angle of 35 90° from the position shown in Fig. 2, so that it will clear the bars 33 and permit the bars to be drawn outwardly and the pins retracted. The form 10 is separable into two longitudinal sections or halves, as shown at 38 and 39, the two 40 halves being held together by the clamps 40 and 41. The structure of this form is described more particularly in my co-pending application, Serial No. 155,877, so that further description herein will be unnecessary.

45 In the making of concrete pipes according to the present method, the form 10 is placed with its axis in a vertical position on the table 11 and centered over the form block 14, where it is secured in place by means of the lugs 17 and 18, 50 which are positioned in grooves 19 and 20 in members attached to the upper and lower supports. The pins 31 are moved inwardly and secured in this protracted position by the retaining members 34, which are moved to the positions 55 shown in Fig. 2. The plunger 25 carrying the packer head 26 is advanced downwardly into the form until the packer head contacts with the block 14.

60 The mix is then poured into the form at the proper rate, and at the same time the packer head 26 is rotated and gradually withdrawn from the form in an upward direction. The concrete mix is relatively dry, as hereinbefore stated, but contains sufficient moisture so that it will prop- 65 erly set. The blades 27 upon the packer head throw the concrete outwardly against the wall of the form so that it is packed tightly against this wall, the mix being fed in at the proper rate to fill the space between the packer head 26 and 70 the wall of the form. When the packer head has been withdrawn from the form, the space outside of the dotted line 28 will have been completely filled with firmly packed concrete, and the space within this line left by the removal of the packer head will, of course, be the opening through the 75

5 pipe. It will be noted that the pins extend inwardly to a point just short of the dotted line 28, so that the openings formed in the wall of the pipe by these pins do not extend quite through the wall.

When the form has been filled, as described, it is released from the machine and carried by a suitable truck to a place where the concrete may be allowed to set. The clamps 40 and 41 are loosened, the pins 31 are withdrawn from the interior of the form, and the parts of the latter are at once removed from the pipe. The withdrawal of the pins 31 is effected by drawing outwardly the bars 33 after the retaining members 34 have been rotated to a position to disengage these bars. The two halves of the form may then be freely removed. It will be understood that the concrete has not yet set, but as it is in a comparatively dry state, and as it has been packed tightly against the wall of the form, it will be self-sustaining until the setting has been completed. The small amount of material left at the inner ends of the openings formed by the pins 31 may be knocked out with a punch or similar tool so as to complete these openings through the wall of the pipe.

25 While I have shown and described a preferred embodiment of my invention and a preferred method of carrying out my improved process, it is to be understood that the invention is not to be limited to all the details shown, but is capable 30 of modification and variation within the spirit of the invention and within the scope of the appended claims.

25 What I claim is:

1. The method of making a perforated concrete 35 pipe which comprises inserting pins through the openings in the wall of a hollow form having the internal shape desired for the external form of the pipe, packing the concrete mix against the wall of the form and around the pins while leaving an opening along the axis of the form, yieldingly holding said pins against outward movement during the packing operation, withdrawing the pins from the interior of the form, and then removing the form from the pipe so formed.

40 2. The method of making a perforated concrete pipe which comprises inserting pins through the openings in the wall of a hollow form having the internal shape desired for the external form of the pipe, packing the concrete mix against the wall of the form and around the pins while leaving an opening along the axis of the form, yieldingly holding said pins against outward movement during the packing operation, withdrawing the pins from the interior of the form, and then removing the form from the pipe so formed prior 45 to the setting of the mix.

50 3. The method of making a perforated concrete pipe which comprises inserting pins through the openings of a hollow form having the internal 55 shape desired for the external form of the pipe, packing the mix tightly against the wall of the form around said pins from the bottom of the form progressively upwardly while leaving an opening along the axis of the form, yieldingly holding said pins against outward movement during the packing operation, withdrawing the pins from the interior of the form, and then removing the form from the finished pipe.

60 4. The method of making a perforated concrete pipe which comprises inserting pins through the opening of a hollow form having the internal shape desired for the external form of the pipe, pouring a concrete mix into the upper end of the form when the latter is in a vertical position, pro- 65 70 75

- jecting a tool into said form from the upper end thereof, and rotating said tool during the feeding of the mix to the form to pack the mix against the wall of the form and around said pins and
- 5 leave an opening along the axis of the form, yieldingly holding said pins against outward movement during the packing operation, then withdrawing the pins from the interior of the form, and removing the form from the finished
- 10 pipe.
5. The method of making a perforated concrete pipe which comprises inserting pins through the opening of a hollow form having the internal shape desired for the external form of the pipe,
- 15 introducing into the upper end of the form while the latter is in a vertical position a rotating tool spaced slightly from the inner ends of said pins, introducing a relatively dry concrete mix into said form from the upper end thereof, and ro-
- 20 tating and gradually withdrawing said tool during the introduction of the mix to pack the latter against the wall of the form and around the pins and leave an opening through the center of the form pipe, yieldingly holding said pins against
- outward movement during the packing operation, and then withdrawing the pins from the interior of the form, and removing the form from the pipe.
6. The method of making a perforated concrete pipe which comprises inserting pins through the opening of a hollow form having the internal shape desired for the external form of the pipe, introducing into the upper end of the form while the latter is in a vertical position a rotating tool 5 spaced slightly from the inner ends of said pins, introducing a relatively dry concrete mix into said form from the upper end thereof, rotating and gradually withdrawing said tool during the introduction of the mix to pack the latter against 10 the wall of the form and around the pins and leave an opening through the center of the form pipe, then withdrawing the pins from the interior of the form, removing the form from the pipe, and thereafter punching out the bottoms of 15 the holes made in the wall of the pipe by said pins.
- 20

JOHN ARBORIO.
